(57) **CLAIM**

The ornamental design for a chair, as shown and described.

DESCRIPTION

FIG. 1 is a perspective view of a chair with a circular base, showing my new design in an exploded closed configuration being detached from the circular base;

FIG. 2 is a front view thereof, showing the chair attached to the base;

FIG. 3 is a rear view of the chair of FIG. 2;

FIG. 4 is a side view thereof, the opposite side being a mirror image thereof;

FIG. 5 is a top view thereof;

FIG. 6 is a perspective view of the chair of FIG. 1, from the same viewing perspective but in an open configuration and attached to the base; and,

FIG. 7 is a side view thereof, in an open configuration, the opposite side being a mirror image thereof.
